Patented November 17, 1903.

UNITED STATES PATENT OFFICE.

THOMAS JOHN WOODWARD, OF BIRMINGHAM, ENGLAND, ASSIGNOR TO CHANCE BROTHERS AND CO., LIMITED, OF WEST SMETHWICK, NEAR BIRMINGHAM, ENGLAND.

DESIGN FOR PLATE-GLASS.

SPECIFICATION forming part of Design No. 36,636, dated November 17, 1903.

Application filed September 14, 1903. Serial No. 173,194. Term of patent 14 years.

To all whom it may concern:

Be it known that I, THOMAS JOHN WOODWARD, a subject of the King of England, residing at Birmingham, in the county of Warwick, England, have invented a new, original, and ornamental Design for Plate-Glass, as shown in the accompanying drawings, in which—

Figure 1 is a face view of a sheet of plate-glass, and Fig. 2 is an edge view thereof.

What I claim is—

An ornamental design for plate-glass as shown.

THOMAS JOHN WOODWARD.

Witnesses:

RICHARD SKERRETT,
ARTHUR JOHN POWELL.
